UNITED STATES PATENT OFFICE.

ARTHUR J. WEISS, OF WEST ORANGE, NEW JERSEY, ASSIGNOR, BY MESNE ASSIGNMENTS, TO MAXI COMPANY, A CORPORATION OF NEW YORK.

CARBURETER.

1,038,040.

Specification of Letters Patent. Patented Sept. 10, 1912.

Application filed January 25, 1912. Serial No. 673,377.

To all whom it may concern:

Be it known that I, ARTHUR J. WEISS, a citizen of the United States, residing at West Orange, county of Essex, State of New Jersey, have invented certain new and useful Improvements in Carbureters, of which the following is a full and complete disclosure.

The object of my invention is to provide an improved carbureter for use in connection with hydro-carbon engines, such as are used on motor vehicles, which shall be more positive and efficient in operation, particularly when the engine is being started or is changing its speed in accordance with the speed of the vehicle or other device being driven by the engine.

The special object of my invention is to provide a carbureter that will obviate the necessity of priming the engine preparatory to starting and at the same time, will not cause a flooding of the carbureter or a waste or overflow of gasoline or similar fuel.

It is also a further object of my invention to permit a rapid and uninterrupted supply of the fuel when the engine is running at its maximum speed, which supply is at all times under complete control in connection with the throttle valve so that the right mixture of fuel and air may be obtained, while at the same time the proportions of the mixture of fuel and air may be varied to suit different conditions.

For a detailed description of one form of my invention, which I at the present time, consider preferable, reference may be had to the following specification and to the accompanying drawings, forming a part thereof of which—

Figure 1 is a side elevation, showing the needle valve and cam chamber casing in vertical section substantially on the line I—I Fig. 2. Fig. 2 is a plan view showing a portion of the casing and needle valve in cross-section substantially on the line II—II Fig. 1. Fig. 3 is a vertical sectional view taken substantially on the line III—III Fig. 2. Fig. 4 is a vertical sectional view through the mixing chamber taken substantially on the line IV—IV Fig. 1. Figs. 5 and 6 are of the nature of diagrammatic views through the mixing cham-

ber of the carbureter, similar to Fig. 3 but, showing the relations of the air and fuel under different conditions of operation. 55

Referring to the drawings: the numeral (1) indicates the casing of the carbureter proper or the mixing chamber and the numeral (2) indicates the casing of the float valve for maintaining an even supply 60 of fuel.

The numeral (3) indicates the pipe which is connected with the main fuel storage tank and its outlet is preferably supplied with a screen (4) for straining the 65 said fuel. The fuel passage (5) opens into the float valve chamber (6) and is controlled by the valve (7) operated by the float (8). The passage (9) extends transversely through the partition or web (10) 70 into the mixing chamber (11) and then is continued upward in a vertical direction as indicated at (12). At the angle between the passages (9) and (12) is placed a needle valve (13) adapted to regulate the amount 75 of fuel desired during the initial action of the carbureter. The passage (12) terminates within the mixing chamber (11) in the form of a nozzle (14), which nozzle is provided at a point slightly removed from its 80 extreme end with diverging openings (15), the purpose of which will be hereafter more particularly pointed out.

The numeral (16) indicates the throttle valve substantially in the well-known "butterfly" form and at one side provided with a slot or recess (17), through which the nozzle (14) is adapted to extend as indicated in Fig. 3 and which may be more or less closed by an adjustable screw-threaded 85 pin (18) passing through the casing (1). This screw-threaded pin (18) is adapted to be held in different angular positions by means of a spring-pressed pawl (19). It will be seen that this pin (18) may be more or less withdrawn or inserted in the mixing chamber (11) thereby more or less filling the recess (17) so that the passage of air past the throttle valve, when the same is closed, may be regulated. 90 95 100

Referring to Fig. 1; it will be seen that the float chamber (6) communicates with a passage (20) which is connected with the needle valve (21) passing through a bush-

ing (22). The stem of the needle valve (21) extends upward through a tube or bushing (23) and is screw-threaded therein as indicated at (24). Above the screw-thread portion (24) is a cylindrical portion provided with longitudinal grooves (25) and a knurled head (26). The grooves (25) cooperate with the spring-pressed pawl (27) to hold the valve-spindle (21) in different angular positions. The bushing (23) carries a fixed collar (28) and is surrounded by a helical spring (29), one end of which rests against the said collar. The upper end of said spring (29) rests against a portion of the casing (30) which surrounds the operating parts of the needle valve. The central pivoted rocking lever (31), provided at one end with a fork (32) which contacts with the collar (28) on the bushing (23), serves to adjust the position of the needle valve. The opposite end of this rocking lever (31) contacts with a cam (33) fixed to the shaft (34) of the "butterfly" valve (16). The shaft (34) extends through the casing (1) and at its upper end is provided with an operating lever (35). It will now be seen that as the throttle valve (16) is more or less opened by the lever (35) the cam (33) will operate the rocking lever (31) to open the needle valve (21) to a corresponding extent, this action being independent of the supply of the fuel to the nozzle (14) except as the latter is affected by the suction of the engine. The web or partition (10) in the mixing chamber (11) is provided with a second horizontal passage (36) which communicates through the passage (37) with the opening upon the needle valve (21). The passage (36) has a series of small conduits (38) branching therefrom, which extend vertically and open into the mixing chamber on the upper side of the web or partition (10) as fully shown in Figs. 3 and 4. The passage (36) also communicates with a passage (39) extending vertically from the passage (36) and this passage (39) communicates with two similar passages or conduits (40) and (41) which also enter the mixing chamber (11) at its side, slightly below the level of the throttle valve (16) when it is in its closed position. The object of these small conduits (38), (40) and (41) will now be described in connection with the operation of the carburetor.

Referring first to Fig. 3; it will be seen that the position of the parts is such as they would assume when the engine is first being cranked or started. At this time a suction or partial vacuum is created in the manifold and the mixing chamber (11) by the movement of the pistons of the engine. This causes the fuel in the passage (12) to be ejected through the nozzle (14) and since the holes (15), at the lower part of said

nozzle, enter the mixing chamber below the closed throttle valve (16) where there is no appreciable vacuum, air will also be sucked through said holes (15) and be ejected together with the gasoline into the mixing chamber (11) above the throttle valve, thus a very rich mixture of air and gasoline is immediately supplied to give the initial or starting mixture to the engine. In this Fig. 3 the arrows are intended to indicate the air, while the dots and dashes indicate the fuel and this designation is also employed in Figs. 5 and 6. It should be noted that at this time the outlets of all the conduits (38), (40), and (41) are below the throttle valve and subject to no suction, no fuel therefore being drawn therethrough. Assuming that it is now desired to increase the supply of the mixture for starting the automobile; the throttle valve (16) is of course turned accordingly until at one point in its movement, it reaches the position shown in Fig. 5. In this position the nozzle (14) acts as before in connection with the passages (15) and discharges above the throttle valve (16) where it is as before, subject to a partial vacuum in the mixing chamber (11). This also draws the fuel through said passage (40) and since the conduits (38) still open below the throttle valve, air will also be drawn into the passages (39) and (40) forming a rich mixture therein, which will immediately be discharged into the mixing chamber (11), thus supplementing the mixture supplied by the nozzle (14). As the motion of the throttle valve is continued, air is admitted to a greater and greater extent, while at the same time the right hand edge of the throttle valve (16) passes successively the outlets of the conduits (41) and (38); thus the suction in the mixing chamber is made effective upon an increasing cross-sectional area of the fuel supply passages and at the same time the air supplied through said passages is diminished in quantity, the increased supply of air however, being obtained by a greater opening of the throttle valve. When the throttle valve is in the position indicated in Fig. 6, it will be seen that fuel is being supplied through all of the passages and since the suction is also operative upon the small radial passages (15), fuel is also supplied through these. This indicates the point of maximum fuel supply and consequently the maximum speed and power of the engine. However, the fuel is at the same time regulated for intermediate degrees of speed by means of the cam (33) controlling the needle valve (21).

From the above it will be seen that I have provided a carburetor which contains two mechanically independent fuel supply systems; one which operates when the engine

is being started and when running slowly, while the other operates in addition thereto while the throttle valve is being opened and controls the supply in two ways up to the maximum speed; these two ways being the bringing into action of successive elements of the fuel outlets and the control of the needle valve.

Having thus described this form of my invention, what I claim and desire to protect by Letters Patent is:

1. A carbureter having a mixing chamber, a throttle valve, and a plurality of fuel outlet passages entering said chamber and arranged to supply a mixture of fuel and air and then liquid fuel progressively as said throttle valve is opened.

2. A carbureter having a mixing chamber, a throttle valve, and a fuel passage having a plurality of branching outlets entering said chamber at separate points below said throttle valve, said outlets being successively caused by the throttle valve as it is opened, first to take air and finally to eject liquid fuel.

3. A carbureter having a mixing chamber, a throttle valve, and a fuel passage having a plurality of branching outlets entering said chamber at separate points below said throttle valve, said outlets being successively caused by said throttle valve as it is opened, to take air, eject mixed air and fuel and finally eject liquid fuel.

4. A carbureter having a mixing chamber, and a fuel passage having a plurality of branching outlets entering said chamber, said outlets being arranged to act initially as air inlet openings and thereafter as liquid fuel outlet openings, and means for controlling the intake of air and the exit of liquid fuel through said outlets.

5. A carbureter having a mixing chamber, and a fuel supply passage having a plurality of branching outlets entering said chamber, said outlets being arranged to act initially as air inlet openings and thereafter as liquid fuel outlet openings, and a valve for controlling the intake of air and the exit of liquid fuel through said outlets.

6. A carbureter having a mixing chamber, and a fuel supply passage comprising a plurality of branching outlets, and a throttle valve located adjacent said outlets, the angular position of which throttle valve controls the initial flow of air and subsequently liquid fuel through said outlets.

7. A carbureter having a mixing chamber, and a fuel passage comprising a plurality of branching outlets, and a throttle valve located adjacent said outlets, the action of which throttle valve causes air to enter initially some of said outlets and to mix with the fuel issuing from others of said outlets and finally a supply of liquid fuel in different positions of said valve.

8. A carbureter having a mixing chamber and a fuel supply passage having a plurality of outlets, a throttle valve, a plurality of said outlets being located adjacent the path of movement of said valve so as to supply air and fuel on the outlet side and to subtract air from the inlet side as the valve is operated.

9. A carbureter having a mixing chamber and two sets of fuel passages entering the same, and a throttle valve, one of said sets of passages having its outlets located so as to operate above said throttle valve when the same is in closed position, and the other set being located so as to be rendered progressively operative to supply air and fuel as the throttle valve is opened.

10. A carbureter having a mixing chamber and two sets of fuel passages entering the same, and a throttle valve, one of said sets of passages having its outlets located so as to operate above said throttle valve when the same is in closed position, and the other set being located so as to be rendered inoperative by the throttle valve to supply fuel when in closed position but effective to supply air and whose effective cross-section to supply fuel is progressively increased as the throttle valve is opened.

11. A carbureter having a mixing chamber and two sets of fuel supply passages entering the same, and a throttle valve, one of said sets of passages having its outlets located so as to operate above said throttle valve when the same is in closed position and the other set having its outlets located so as to be made progressively operative by the throttle valve to successively supply air and fuel as said valve is opened.

12. A carbureter having a mixing chamber and two sets of fuel passages entering the same, and a throttle valve, one of said sets of passages being so located as to be operative above said throttle valve when the same is in closed position, both of said sets having outlets located so as to be made progressively operative by the throttle valve to supply air and fuel as said valve is opened.

13. A carbureter comprising a throttle valve having an opening therein, a liquid fuel supply, two passages leading therefrom, one of which terminates in a nozzle which passes through said opening to the engine side of said valve when the same is in its closed position, and means for moving said valve to a position above said nozzle.

14. A carbureter comprising a disk throttle valve having an opening therein, a liquid fuel supply, two passages leading therefrom, one of which terminates in a nozzle which passes through said opening to the engine side of said valve when the same is in its closed position, and means for moving said disk to a position above said nozzle.

15. A carbureter having a mixing cham-

ber, a central transverse web therein, having two horizontal fuel passages therethrough, an outlet passage communicating with one of said horizontal passages, a nozzle connected with said outlet passage, the other horizontal passage communicating with a plurality of outlet passages branching therefrom.

16. A carbureter having a mixing chamber, a central transverse web therein having two horizontal passages therethrough, an outlet passage communicating with one of said horizontal passages, a nozzle connected with said outlet passage, and a throttle valve beyond which said nozzle extends when the valve is closed, the other horizontal passage communicating with a plurality of outlet passages branching therefrom and whose

ends are located adjacent the path of movement of said valve.

17. A carbureter having a mixing chamber, a disk throttle valve pivoted transversely therein, a central transverse web in said chamber and having a plurality of branching passages therethrough, the outlets of said passages being located below said valve when it is closed and made successively operative by the edge of said valve as it is opened.

Signed this 23rd day of January, 1912.

ARTHUR J. WEISS.
